UNITED STATES PATENT OFFICE.

ELVIN FARNAM, OF LOS ANGELES, CALIFORNIA.

SCARECROW.

1,329,044.

Specification of Letters Patent. Patented Jan. 27, 1920.

Application filed April 8, 1919. Serial No. 288,490.

To all whom it may concern:

Be it known that I, ELVIN FARNAM, a citizen of the United States, residing at Los Angeles, in the county of Los Angeles and 5 State of California, have invented new and useful Improvements in Scarecrows, of which the following is a specification.

My object is to make a scarecrow, and my invention consists of the novel features 10 herein shown, described and claimed.

Figure 1 is a side elevation showing a scarecrow embodying the principles of my invention in use.

Fig. 2 is a vertical cross section on the line 15 2—2 of Fig. 4.

Fig. 3 is a side elevation on the same plane as Fig. 1, and as seen looking in the direction indicated by the arrow 3 in Fig. 4.

Fig. 4 is a top plan view as seen looking 20 in the direction indicated by the arrow 4 in Fig. 3.

Fig. 5 is a sectional detail showing a modified form of support.

The scarecrow 1 is made in imitation of a 25 large bird, such as a bird of prey and is loosely mounted to be fluttered by the wind.

The breast portion 2 of the scarecrow has a flat top 3 and a lower face 4 which is curved to a semicircle in cross section and 30 elongated in side elevation. A central opening 5 is formed vertically through the breast 2. The feathers 6 are arranged with their stems 7 fitting upon the flat face 3 around the edge, and a plate 8 is placed downwardly 35 upon the stems and held in position by screws 9 inserted through the plate into the

breast 2. A small opening 10 is formed through the center of the plate 8.

The post 11 is nailed to the body of a tree 12 in a vertical position, a bore 13 is formed 40 from the upper end of the post 11, a pin 14 is driven tightly into the bore 13, and the pin 14 fits loosely in the central opening 5, and the point 15 of the pin extends part way into the opening 10, so that the scarecrow 45 will rotate and vibrate by the action of the wind.

In Fig. 5 the timber 16 may be mounted in any suitable way. The cord 17 is placed through the opening 10, and a knot 18 50 formed upon its lower end and the upper end is inserted through the timber 16 and a knot 19 formed upon its upper end, so that the scarecrow may be moved around by the wind to the limits of the cord 17. 55

Various changes may be made without departing from the spirit of my invention as claimed.

I claim:

A scare-crow comprising a body member 60 having a flat top, feathers mounted at their quill ends upon the flat top of the body member and extending outwardly, a plate adapted to cover and clamp down to the body member to hold the feathers and a pivot 65 bearing in the plate adapted to ride upon a pivot extending upwardly through a hole in the body member so that the scare-crow will lie horizontally and flutter in the wind.

In testimony whereof I have signed my 70 name to this specification.

ELVIN FARNAM.
